UNITED STATES PATENT OFFICE.

ALFRED F. C. LOTZ, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS.

SWITCH-OPERATING MECHANISM.

Application filed May 1, 1924. Serial No. 710,334

This invention relates to mechanism for operating switches, and more especially to an improved device for closing and opening switches, particularly switches of the oil 5 type, although the invention is not limited thereto.

According to my invention, a rotary shaft is employed which, in the preferred form of the invention, is the operating shaft of the 10 switch, and I provide, in conjunction with said shaft, means for automatically or manually tripping the switch open and for manually restoring the switch to closed position. The automatic trip is operable without interfering with the manual opening and closing 15 mechanism. The automatic mechanism is automatically set in extended position by the movement of the manual parts upon being released, and the switch is closely manually 20 through the automatic tripping mechanism with an accompanying automatic resetting of said mechanism with the manual closing movement, which also resets the manual operating parts.

The mechanism employed, according to my invention, is of simple, rugged and inexpensive construction. The operating mechanism is characterized by a minimum of inertia so that the oil switch may open with great 25 rapidity, and in the closed position of the switch, it offers a very substantial resistance to opening and provides a great leverage through which a powerful closing movement is imparted. The strain upon the 30 parts is low and long life and satisfactory operation are assured, and the operating parts are all supported independently of the enclosing casing so that proper alignment and positioning may be secured in spite of 35 disalignment and inaccuracies in the casting.

In my co-pending application (Case 5), Serial No. 684,278, filed January 4, 1924, I have shown an oil switch employing a rocking 45 or rotary shaft which is adapted to be operated by the present invention, but it will be understood that the present invention is not limited to the combination of that particular switch with the present mechanism, but is intended to cover the present mechanism in combination with that type or any other type of switch which employs a rocking or rotary shaft.

To acquaint those skilled in the art with 50 the manner of constructing and operating

my invention, I shall now describe an embodiment of the same in connection with the accompanying drawings.

In the drawings:

Fig. 1 is an end elevational view partially 60 in section of a trip and reset mechanism embodying my invention showing the parts in set position;

Fig. 2 is a similar view showing the parts 65 in the positions assumed upon the occurrence of an automatic trip;

Fig. 3 is a similar view showing the parts 70 in the positions assumed upon tripping the switch manually or upon lowering the operating member upon the occurrence of an automatic trip for the purpose of resetting the parts;

Fig. 4 is a vertical section taken on the line 4—4 of Fig. 1;

Fig. 5 is a vertical section on line 5—5 of 75 Fig. 1;

Fig. 6 is a horizontal section on line 6—6 of Fig. 1;

Fig. 7 is a horizontal section on line 7—7 80 of Fig. 1;

Fig. 8 is a vertical section on line 8—8 of Fig. 7;

Fig. 9 is a detail section on line 9—9 of 85 Fig. 1;

Fig. 10 is a detail section on line 10—10 of Fig. 1;

Fig. 11 is a detail section on line 11—11 90 of Fig. 1;

Fig. 12 is a detail section on line 12—12 of Fig. 1;

Fig. 13 is an isometric view of the toggle 95 latch lever;

Fig. 14 is an isometric view of the lever for tripping the toggle latch lever and latching the operating lever; and

Fig. 15 is an isometric view of the clevis 100 toggle link.

The square shaft 5 prolonged forms the shaft of the switch mechanism, such as disclosed in my above referred to co-pending 105 application. Rocking of this shaft through substantially 45° serves to separate the contacts of the switch to the desired extent, and movement of the same in the reverse direction closes the contacts. Thus, by small 110 rocking movement, the switch is completely opened or closed. The shaft 1 may have suitable stop means for limiting its rocking motion in each direction, or the stop means may be associated with the switch itself.

The spring which operates the shaft 5 is contained within the switch, as will be apparent from the drawings of said co-pending application, and it is not shown in the present drawings. The switch operating mechanism is housed within a casing comprising a removable cover or casing part 6 having a side or back 8 which forms a shaft bracket and has an integral bottom 7. The casing 5 is shown mounted upon an external supporting channel 9, as by means of a bracket 10 formed integral with the back 8 and bolted or otherwise suitably secured to the channel 9. The back 8 may be secured in place by bolts 12 cooperating with suitable lugs 13 on the casing.

I shall describe first the latch mechanism for holding the shaft 5 against rotation under the tension of the spring means in 20 the switch, which spring means tends to rotate the shaft in a counterclockwise direction, as viewed in Figs. 1, 2 and 3.

Fixed on the shaft 5 to turn or rock therewith is a shaft lever 15. The lever 15 has 25 formed integral therewith, as shown in Fig. 9, a sleeve or collar 16 which extends axially along the shaft 5 and has square openings through its opposite ends with which the square shaft 5, extending therethrough, 30 operates to lock the shaft and lever 15 for rocking movement together. Loose on the collar or sleeve 16 of the lever 15 for free rotation thereabout is a collar or sleeve 18 having formed integral therewith a radial arm 20. The arm 20 is of honey-combed formation for a purpose which will hereinafter appear. Pivoted in the outer end of the arm 20, upon a pin 22, is a latch and toggle latch tripping lever 24.

40 Lever 24 has at its inner end a detent 25 which normally engages a shoulder 26 on a latch arm 28 and holds the arm 20 in the position shown in Fig. 1. Arm 28 is pivoted at 29 upon a pin secured in spaced lugs 30 projecting horizontally from a latch bracket 31, which bracket 31 is mounted in upright position upon the bottom of the casing 6. A coiled spring 32 interposed between the upper end of the bracket 31 and the 45 upper end of the arm 28 on suitable aligning studs holds the upper end of the arm projected from the bracket. The lower end of the arm 28 projects downwardly at 34 for cooperation with an adjusting screw 35, by 50 means of which the position of the latch shoulder at the upper end of the arm may be adjusted as desired.

The free end of the lever 24 is turned out 60 at 36 to lie in the path of downward movement of a stud or pin 37 on the operating bar 38, and formed on the under surface of this turned-out end 36 is a nose 39. A coiled spring 40 interposed between an integral abutment 41 on arm 20 and an abutment 42 65 on lever 24 on suitable aligning studs tends

to swing the lever 24 in a counterclockwise direction and the detent 25 into latching engagement with shoulder 26.

The shaft 5 is restrained from turning under the action of the spring means in the switch by means of a toggle comprising a toggle arm 44 pivoted at one end on the pin 22 and at its opposite end upon a pin 45 in the bifurcated end of a clevis toggle link 46, the opposite end of which link 46 is pivoted by a pin 47 to the free end of the shaft arm 15. Integral with the inner end of the toggle arm 46 is a lateral lug 50, and for the purpose of holding the toggle arms 44 and 46 in extended 180° position, as shown in 80 Fig. 1, I provide a toggle latch and releasing lever 52. The lever 52 is loose on a pin 53 secured in the arm 20 and it extends through one side of the honey-combed formation of said arm, as shown in Figs. 5, 7 and 11. 85 The upwardly extending arm 54 of the lever 52 is stepped or shouldered at 55 and this step or shoulder 55 normally engages under the lug 50 and holds the toggle arms 44 and 46 in extended position. The upper end of 90 the arm 54 terminates in a head inclined at 56 for cooperation with the nose 39 of lever 24 when the lever 24 is depressed. The lever 52 has integral, downwardly extending curved arm 58 for the purpose of automatically tripping the toggle latch, as will hereinafter appear. Integral with the free end of arm 20 is a lateral projection 60 which overlies the lever 24 and arm 44 and limits the turning of said lever and arm in 100 a counterclockwise direction about pin 22.

From the foregoing, it is now apparent that opening of the switch under the action of the switch spring is normally opposed by the toggle arms 44 and 46 and that said arms 105 act in compression and are in a straight line and of maximum effectiveness at such time. The detent 25 holds the arm 20 and thereby the pivot end 22 of the toggle in the positions shown. Any tendency toward upward swinging of the shaft arm and of the link 46 under the action of the switch spring is prevented by the formation and positioning of the lug 50 and latch shoulder 55.

The main operating bar 38, which carries 115 the operating pin or stud 37, extends down vertically through an opening 65 in the bottom of the casing 6. It extends through the forward honey-combed side of arm 20 and has an elongated vertical slot 66 through 120 which the enlarged portion of the pin 53 extends. A remote controlled operating lever, such as that shown in my co-pending application, Serial No. 673,465, filed November 8, 1923, or any other suitable operating 125 lever, may be provided for lowering and raising the operating bar 38.

Assume that the parts are in the position shown in Fig. 1 and that the switch is closed, the switch may be opened manually by low- 130

ering or moving the bar 38 downwardly as by means of the operating handle and connected parts (not shown). Upon downward movement of bar 38, slot 66 travels freely 5 over pin 53 and the stud 37 is moved into engagement with the upper surface of the out-turned end 36 of lever 24. Further downward movement of the bar 38 swings the lever 24 in a clockwise direction about the pin 22. By reason of the relative lengths 10 of the detent and releasing arms of lever 24, the detent 25 remains in engagement with shoulder 26 until the nose 39 engages the inclined upper end 56 of the arm 54 and 15 swings said arm in a counterclockwise direction to release the shoulder 55 from the toggle lug 50. The detent 25 thereupon disengages shoulder 26 and the arm 20, with its associated latch and trip mechanism, drops 20 into the position shown in Fig. 8.

Immediately upon releasing shoulder 55 from lug 50, the toggle is free to break under its own weight and under the action 25 of the switch spring and it drops and automatically straightens itself between pins 22 and 47 for the resetting operation.

Now, in order to reset; that is, close the switch after a manual tripping, the operating member 38 is moved upwardly through the 30 operating mechanism. When the lower end or the slot 66 reaches the pin 53, the free arm 20 is swung upwardly through this engagement. This upward movement acts from the pin 22 through the toggle arms 44 35 and 46, which have automatically straightened or set themselves to turn the shaft 5 through the shaft arm 15 in a clockwise direction against the tension of the switch spring. The straight condition of the arms 40 44 and 46 acting through the shaft arm 15 provides a relatively great leverage for moving the switch to closed position with a relatively small power application on the switch operating member. As soon as the 45 reset position has been obtained, the detent 25 engages over the shoulder 26, the spring 32 permitting the arm 28 to yield sufficiently to permit the detent 25 to move into latched position. As the detent 25 holds its engagement 50 with shoulder 26, the free arm 20 is held in the position shown in Fig. 1. As the arm 20 reaches this position, the toggle arms 44 and 46 reach their straight line position of Fig. 1 between the pins 22 and 47, and the 55 shoulder 55 of the latch and trip lever 52 swings into engagement under lug 50 and holds the toggle which holds the switch closed in the position shown in Fig. 1. Consequently, the switch is closed and held 60 closed by the toggle arms 44 and 46, and the toggle arms are held in the position holding the switch closed by the latch and release lever 52, the detent 25 holding the arm 20 and pin 22 in corresponding positions. 65 Upon closing the switch and setting the

parts as described, the pin 37 assumes the position shown in Fig. 1 and the out-turned end 36 of lever 24 is positioned below said pin and in the path of downward movement thereof to be engaged and swung into cooperation with the upper end of the arm 54 of lever 52, as previously described. 70

I shall now describe the automatic trip mechanism for tripping the shoulder 55 out of holding engagement with lug 50 to permit 75 the toggle to break under its own weight and under the action of the switch spring so that the switch may be automatically opened, as is desired for overloads and the like.

The automatic tripping mechanism is 80 mounted upon a shelf 70 integral with and projecting horizontally inwardly from the back 8. The back 8 forms a shaft bracket having a boss 72 in which the shaft is journaled at one end of the casing. At the opposite end of the casing, the shaft 5 is journaled in a boss 73 on the cover or casing member 6, a bronze or other suitable bushing 73' being provided in boss 73 for the outer end of collar 16, as shown in Fig. 9. 85 The shelf 70 has vertical webs 74, and mounted upon the shelf as by bolts 75 is a solenoid supporting frame 76. The solenoid supporting shelf, with the shaft bracket 8 and the bracket 31, obviously supports the entire mechanism independently of the casing or cover 6, so that alignment and proper cooperation of the various parts is in no way dependent upon the accuracy or condition of 90 said cover. 100

The solenoid supporting frame 76 is of open formation, with ends 78 and a flat top 79 having upright ribs 80. Mounted upon the top 79 of frame 76, by means of screws 82, are magnet yokes 83, and mounted in each yoke 83 is a magnet 85. Each magnet 85 has a fiber tube about which and between the fiber heads is the winding 86. Operable in the lower end of the fiber sleeve is the movable core or plunger 90 having adjustable 105 operating stems 91 threaded into and depending therefrom. Threaded through the upper legs of the yokes 83 and extending down into the solenoids are plugs 92, which may form adjustable stops for limiting the 110 action of the plungers 90. 115

The stems 91 extend down through slots 93 in a knock-off lever 94 shown more clearly in Fig. 6, and have heads 95 at their lower ends, which heads underlie the lever 94. 120 The knock-off lever 94 is pivoted at its opposite ends through integral lugs 96 and bolts 97 to the ends 78 of the solenoid supporting frame, and said lever 94 has an integral arm 98 offset to underlie the down-curved arm 58 of the latch and trip lever 52. The conductors for the solenoids may be led in through an opening 102 in back 8, said opening being threaded to receive suitable 125 insulating bushing or the like. 130

The operation of the automatic tripping mechanism is as follows:

Assume that the parts are in the position shown in Fig. 1, the lever 52 holding the toggle extended and the detent 25 holding the free arm 20 in the positions shown. Assume that the solenoids 85 are energized as by the occurrence of an overload. The plungers 90 will be raised, raising the knock-off lever 10 about its pivots 97 and thereby the offset arm 98 of the knock-off lever into engagement with the arm 58 of the toggle latch and release lever 52. The lever 52 is thereby swung in a counterclockwise direction about 15 the pin 53 to release the latch shoulder 55 from the lug 50. The toggle arms are immediately freed to break, and under their own weight and the tension of the switch spring, they break downwardly into the 20 dotted line positions of Fig. 1 and permit the shaft 5 to rock in a counterclockwise direction with an accompanying opening of the switch.

It should be noted that automatic tripping is permitted without tripping or moving the 25 free arm 20 or the latch and trip means associated therewith. The number and inertia of the moving parts upon automatic tripping of the switch is thereby maintained at a minimum.

30 For resetting the switch after the occurrence of an automatic trip, the operating member 38 is moved downwardly to release the detent 25 and permit the arm 20 and latch mechanism associated therewith to 35 drop into the position shown in Fig. 3, as already explained. As the arm 20 drops to its free or released position of Fig. 3, the toggle arms 44 and 46 automatically straighten and set themselves for the resetting operation, as already explained in connection with the manual tripping and resetting of the switch. With the parts in this 40 position, the switch is reset after an automatic trip in the same manner as already explained after a manual tripping of the switch. The toggle latch lever 52 has an arm 105 which, upon clockwise swinging of the arm, cooperates with the sleeve or collar 18 of arm 20 and prevents swinging of the 45 latch arm past its position for proper latching engagement of shoulder 55 with lug 50.

The automatic tripping and opening of the switch may be permitted, as previously indicated, without interfering with the 55 manual holding and resetting mechanism so that the number and inertia of the moving parts upon the occurrence of an automatic trip is reduced to a minimum. The toggle linkage is particularly adapted for holding the switch closed. When extended, as shown in Fig. 1, it offers a very substantial resistance to its collapse and thereby a very substantial resistance and effective lock against opening of the switch. The toggle mechanism is easily and quickly broken, and it per-

mits a relatively high velocity of opening movement with relatively light moving parts. The toggle mechanism provides a great closing leverage and the closing motion imparted therethru is very powerful. 70 The automatic trip simply operates to release the toggle and permit it to break, while the manual operating mechanism breaks the toggle and removes one point of support thereof, and at the end of the downward 75 motion of the manual operating parts, the toggle automatically straightens and sets itself to hold the parts positively in open position and for the resetting operation. Upon automatic tripping the toggle is 80 broken as shown in dotted lines in Fig. 1 and the downward movement of member 38 straightens the toggle into its resetting position.

I do not intend to be limited to the details 85 shown or described.

I claim:

1. In combination, a rock shaft, a rocking member on said shaft, a detent for holding said rocking member set, a toggle connected between said rocking member and the shaft and adapted when the rocking member is set to hold the shaft in one position, latch means for holding said toggle in holding position, automatic means for 95 tripping out said latch to release the toggle and shaft and manually operable means for tripping said detent and latch to release the rocking member and the toggle.

2. In combination, a rock shaft, a rocking member on said shaft, a detent for holding said rocking member set, a toggle connected between said rocking member and the shaft and adapted when the rocking member is set to hold the shaft in one position, latch means for holding said toggle in holding position, automatic means for 100 tripping out said latch to release the toggle and shaft and manually operable means for tripping said detent and latch to release the rocking member and the toggle, said 105 manually operable means being operable to reset the switch through said toggle means.

3. In combination, a rock shaft, a rocking arm free on said shaft, a toggle connected 115 between said arm and the shaft and having an extended position for holding the shaft in one position, a latch arm pivoted on said free arm and adapted for holding the toggle extended, a detent for holding the free arm 120 in one position and an operating member adapted for releasing said detent and the latch arm through said detent.

4. In combination, a rock shaft, a rocking arm free on said shaft, a toggle connected 125 between said arm and the shaft and having an extended position for holding the shaft in one position, a latch arm pivoted on said free arm and adapted for holding the toggle extended, a detent for holding the free arm 130

in one position, manual means for releasing said detent and the latch arm through said detent and automatic means for releasing the latch arm independently of said detent 5 and free arm.

5. In combination, an operating shaft, means tending to rock the shaft in one direction, a rocking arm free on said shaft, toggle means connected between said arm 10 and the shaft for holding the shaft against action by said rocking means, latch means for holding the toggle in shaft holding position, automatic means for knocking off said latch means and manual means for knocking 15 off said latch means and tripping said arm, said manual means being operable to reset the shaft through said arm and toggle.

6. In combination, an operating shaft, means tending to rock the shaft in one direction, toggle means for holding the shaft 20 against action by said rocking means comprising links pivoted together and tending to collapse under their own weight and under the action of said shaft rocking means, 25 a latch for holding the toggle extended, electromagnetic means for tripping said latch and manual means for tripping the latch and resetting it and the toggle holding means.

30 7. In combination, an operating shaft, means tending to rock the shaft in one direction, a rocking arm free on the shaft, toggle means comprising links pivoted together and connected between said free arm and the 35 shaft and tending to collapse under their own weight and under the action of said shaft rocking means, a latch for holding the toggle extended, a detent for holding the free arm set, said latch having an arm under- 40 lying said detent and an operating member having means normally overlying said detent and operable to release the detent and latch.

8. In combination, an operating shaft, 45 means tending to rock the shaft in one direction, a rocking arm free on said shaft, a holding toggle between said arm and the shaft, a detent for holding said arm set, a latch for holding the toggle in holding 50 position, automatic means for tripping said latch and manual means for tripping the latch and detent.

9. In combination, an operating shaft, means tending to rock said shaft, a rocking 55 arm free on the shaft, a holding toggle between said arm and an arm secured to the shaft, a latch pivoted on the free arm and adapted for holding the toggle in shaft holding position, and a detent pivoted on 60 the free arm and overlying said latch for holding the free arm set.

10. In combination, an operating shaft, means tending to rock the shaft, a rocking arm free on the shaft, an arm secured to the 65 shaft, a holding toggle between said rocking

arm and the arm secured to the shaft, a detent pivoted on the free arm and adapted for holding said arm set, a pin, a vertically movable operating member having an operating stud overlying said detent and a latch 70 pivoted on the free arm on said pin, said pin extending through a slot in the operating member and adapted for holding the toggle in shaft holding position.

11. In combination, a rocking shaft, means 75 tending to rock said shaft, an arm free on said shaft, a toggle pivoted to said arm and connected between it and the shaft for holding the shaft against the action of said rocking means, and a detent pivoted to said arm 80 and adapted for holding the arm set, said arm having means overlying the toggle and said detent for limiting their movement in a direction opposite that of their releasing movement.

12. In combination, an operating shaft, means tending to rock the shaft, a rocking arm free on the shaft, an arm secured to the shaft, a holding toggle between said rocking arm and the arm secured to the shaft, and a 90 detent pivoted on the free arm and adapted for holding said arm set.

13. In combination, an operating shaft, means tending to rock the shaft in one direction, a rocking arm loose on the shaft and 95 held against movement about said shaft, holding means connecting the arm and the shaft and normally holding the shaft against turning in one direction, a latch pivoted on the arm and holding said holding means in 100 operative position, and an electromagnetically operated lever disposed to knock out the latch and release said holding means when said lever is operated.

14. In combination, a rocking shaft, a 105 rocking arm free on said shaft, a detent pivoted on said arm, a latch arm, means interposed between said free arm and said detent for normally holding said detent in engagement with said latch arm for holding 110 said free arm in set position, and connections between the shaft and the arm acting to hold the shaft against rotation when said arm is in set position and releasing the shaft for turning movement when the arm is released.

15. In combination, a casing, an operating shaft, means outside of said casing tending to rock the shaft, a rocking arm free on said shaft, a holding toggle connected to the shaft 120 and the arm for holding said shaft set, a detent for holding said arm set, a latch for holding the toggle in holding position, and manually operative means extending through said casing for tripping the latch 125 and detent.

16. In combination, a casing, a rocking shaft, means tending to rock said shaft, means for holding said shaft against the action of said rocking means, latch means 130

for holding said holding means in holding position, said latch means having a pair of arms, electromagnetic means within said casing adapted to cooperate with one arm of said latch, and manually operative means extending through said casing adapted to cooperate with the other arm of said latch for releasing said holding means.

17. In combination, a rockably mounted 10 operating shaft urged in switch opening direction, an arm free on the shaft, an arm fixed on the shaft, a holding toggle connecting said arms, means holding the free arm set, means holding the toggle extended, manually operated means for releasing the free arm and the toggle and for resetting said toggle and fixed arm, and automatic means for releasing the toggle.

18. In combination, a rockably mounted 20 operating shaft urged in switch opening direction, a toggle lever connected at one end to the shaft, a normally fixed abutment holding the other end of the toggle lever

against movement, means holding the toggle lever extended, said toggle lever when extended holding the shaft in switch closing position manually operated means for releasing the toggle lever, and automatic means for releasing said toggle lever.

19. In combination, a rockably mounted 30 operating shaft urged in switch opening direction, a toggle lever connected at one end to the shaft, a normally fixed abutment holding the other end of the toggle lever against movement, releasable means normally holding the toggle lever extended, said toggle lever when extended holding the shaft in switch closing position, manually operated means for releasing the toggle lever, and automatic means for releasing said holding 35 means and causing breaking of the toggle lever.

In witness whereof, I hereunto subscribe my name this 26 day of April, 1924.

ALFRED F. C. LOTZ.
